UNITED STATES PATENT OFFICE.

CARL C. MOON, OF WESTBORO, OHIO.

MOTOR.

1,378,264.

Patented May 17, 1921.

Application filed December 11, 1919. Serial No. 344,057.

To all whom it may concern:

Be it known that I, CARL C. MOON, a citizen of the United States, residing at Westboro, in the county of Clinton and State of Ohio, have invented certain new and useful Improvements in Motors, of which the following is a specification.

This invention relates to motors, and the primary object of the invention is to provide an improved fluid operated rotary motor, which is so constructed as to be perfectly balanced and generate more power with a given amount of fluid energy than has heretofore been considered possible.

Another object of the invention is to provide a motor embodying a rotor carrying a plurality of improved blades, the blades being associated with the rotor in such manner that the same can be turned, so that the wear thereon will be equally distributed throughout the same.

Another object of the invention is to provide an improved type of rotary motor of the above character, which will be light in weight, durable and efficient in use, one which will be simple and easy to manufacture, and one which can be placed upon the market at a reasonable cost.

Other objects of the invention will appear in the following detailed description taken in connection with the accompanying drawings, in which drawings:

Figure 1 is a side elevation of the improved motor.

Fig. 2 is a vertical longitudinal section through the same.

Fig. 3 is a vertical transverse section taken on the line 3—3 of Fig. 2.

Fig. 4 is a detail horizontal section taken on the line 4—4 of Fig. 2.

Fig. 5 is a detail section taken on the line 5—5 of Fig. 2.

Fig. 6 is a plan view of one of the improved blades, and

Fig. 7 is a diametric section through the same taken on the line 7—7 of Fig. 6.

Referring to the drawings in detail, wherein similar reference characters designate corresponding parts throughout the several views, the letter A indicates the improved motor which includes the frame B,

the rotor C, the blades D, and the blade carrying means E.

The frame B includes a pair of spaced circular side plates 10, having concentric bearings 12 for the reception of the shaft 13 to which is keyed or otherwise secured the rotor C.

The bearings 12 are provided with suitable oil cups 14 so that the shaft may be properly lubricated. The side plates 10 are provided with outwardly extending peripheral flanges 15, to which are adapted to be secured the rim 16 of the frame, which is preferably made of two semi-circular sections 17, and 18. The lower section 18 is provided with an enlarged attaching base 19 provided with attaching flanges 20, by means of which the motor may be bolted or otherwise secured to a suitable support.

The annular rim 16 includes a longitudinally extending transversely curved body portion 21, which is adapted to lie intermediate the side plates and outwardly extending attaching flanges 22 which overlie the flanges 15 and the flanges are adapted to be secured together by suitable bolts 23 or other removable fastening elements.

The rim 16 at diametrically opposite points is gradually increased in depth as at 24 so as to permit the blade D to project farther from the rotor at these points for a purpose which will be hereinafter more fully described. The sections 17 and 18 of the annular rim 16 are provided at their meeting portions with outwardly extending abutting flanges 25, which are bolted or otherwise secured together as at 26.

Each section of the annular rim 16 is provided at its opposite relatively deep portion 90 with oppositely extending tangentially disposed outlet or exhaust pipes 27, which are formed of relatively large diameter, so as to permit the spent operating medium to pass out into the atmosphere. Each section of the annular rim 16 is also provided with oppositely disposed tangentially arranged inlet pipes 28, which are arranged adjacent to the relatively narrow portion of the rim and these inlet pipes are provided with a 100 relatively small bore, so as to permit the steam or other fluid pressure to be injected

against the blade under a relatively high pressure. The inlet and exhaust openings communicating with the rim are preferably oval shaped as at 29, so as to prevent the catching of the blades D in the same. The inlet and outlet pipes 27 and 28 are provided with threaded terminals so as to permit the connection of the same with suitable pipes. Any preferred type of means can be provided for governing the amount of fluid pressure emitted to the inlet pipes 28.

The rotor C includes a hub 30, a concentric relatively thick rim 31, and a plurality of connecting spokes 32. The hub 30 receives the drive shaft 13, as heretofore stated. The periphery of the rim 31 is provided at equidistantly spaced points with inwardly extending slots 33 for the reception of the blades D. Each of the blades D includes a circular solid body 35, having an annular groove 36 formed therein for the reception of the ordinary or any preferred type of expansion piston rings 37, which are adapted to bear against the inner surface of the rim 25 to prevent the escape of the fluid pressure from between the rim and blade.

As clearly shown in Fig. 2 of the drawings, the blades D are arranged radially in relation to the rotor C and when the rotor C is in motion, the blades will be normally held in engagement with the inner surface of the rim by centrifugal force. However, to positively hold the blade in operative position during the starting of the motor, the blade operating means E is provided. The blade operating means E includes a follower 38, which is slidably mounted in the inwardly extending recesses 33 formed in the rim, and each of the followers are provided with arcuate depressions for the reception of the inner ends of the blades D. The followers 38 are normally urged outwardly by means of expansion coil springs 39, and the inner walls of the recesses 33, and the inner face of the followers 38 are provided with sockets 40 for the reception of the terminals of the coil springs to prevent displacement thereof. The blades D are free to turn in relation to the followers 37 and in operation 50 of the motor the blades D will have a tendency to be moved in the follower and thus present a new wearing face to the rim and thus prevent one portion of the blade from becoming worn more than the other portions.

In operation of the improved motor, fluid pressure such as steam or compressed air is emitted through the inlet pipes 28 and the same hits the blades D and rotates the rotor 60 C. As the blades ride past the inlet openings or pipes 28, the same will ride outwardly owing to the gradual increased depth of the rim 16 and thus permit of expansion of the steam or air until the outlet openings or 65 pipes 27 are reached, at which time the

steam or air will pass out into the atmosphere.

If found desirable, the exhaust ports 27 may be connected to the inlet pipes of another motor, so as to utilize the exhaust steam or compressed air as it has been found that in some instances the steam has not been spent or expanded to its maximum point.

From the foregoing description it can be seen that an improved rotary motor has been provided of an exceptionally durable and simple construction which will efficiently perform the purpose intended. Suitable packing strips or gaskets 41 may be interposed between the ring 16 and the plates 10 so as to prevent the leakage of the fluid pressure from the casing. The inlet and outlet pipes 27 and 28 may be provided with suitable web so as to effectively brace the same if so desired.

Changes in details may be made without departing from the spirit or scope of my invention; but,

I claim:

1. In a rotary engine, a casing, a rotor mounted in the casing, the rotor having a plurality of equi-distantly spaced inwardly extending slots formed therein, a blade rotatably and slidably mounted in each one of the slots, and inlet and exhaust ports formed in the casing.

2. In a rotary engine, a casing, a rotor arranged in the casing, said rotor having a plurality of equi-distantly spaced slots formed therein, spring pressed followers mounted in the slots, and blades mounted in the slots and arranged to be engaged by said followers, said blades being mounted for movement independent of said followers.

3. In a rotary engine, a casing, a rotor mounted in the casing, said rotor having a plurality of inwardly extending slots formed in the periphery thereof, circular blades slidably mounted in the slots, and spring pressed followers arranged in the slots formed independent of said blades.

4. In a rotary engine, a casing, a rotor mounted in the casing having a plurality of inwardly extending slots formed in the periphery thereof, a follower slidably mounted in each one of the slots, spring means normally urging the followers outwardly, the outer faces of the followers being provided with arcuate depressions, and disk shaped blades slidably mounted in said slots and rotatably seated in said arcuate depressions formed in the followers.

5. In a rotary engine, a casing, a rotor mounted in the casing, blades slidably carried by the rotor, means for sliding the blades in the rotor, inlet ports communicating with the casing at the point where the blades are in their innermost positions, and exhaust ports communicating with the cas-

ing at the point where the blades are in their extended positions.

6. In a rotary engine, a casing including a rim, a rotor mounted in the casing, blades 5 slidably and rotatably carried by the rotor, the rim being shaped to force the blades inwardly at diametrically opposite points,

inlet ports communicating with the casing at the points where the blades are forced inwardly, and exhaust ports communicating 10 with the casing where the blades are in their extended positions.

CARL C. MOON.
